UNITED STATES PATENT OFFICE

2,188,897

DESK CONSTRUCTION

Irving B. Hall, Chicago, Ill.

Application December 7, 1936, Serial No. 114,653

13 Claims. (Cl. 311—21)

My invention relates to that class of devices generally known as writing desks or the like, and more particularly to a device for installation and use on automobiles, aeroplanes, railway cars, busses and other vehicles.

The invention has as an object, the production of a device of the kind described that is simple, compact, inexpensive, durable and particularly convenient for the purpose intended.

10 The invention has among its further objects the production of a folding desk, that is to say, it may be moved to operative position or folded back out of the way in a substantially dust-proof container.

15 It has particularly as an object a device of the kind described, which is readily available for use, and when in operative position is rigidly and effectively supported without the use of a depending leg or legs, which in a congested or 20 limited space, such as the front of an automobile at the dash, would be in the way and be uncomfortable to the occupant of the seat.

For use in automobiles, the present invention is particularly desirable for the convenience of 25 salesmen and others who find the use of a table or desk particularly desirable and convenient in making out reports or for other correspondence.

The present invention may also be used as a serving table if and when desired.

30 Practical embodiments of the present invention are shown for illustrative purposes in the accompanying drawings in which:

Fig. 1 is an elevational view of my improved desk construction shown in operative position, 35 and illustrating the manner of supporting the structure in relation to portions of an automobile;

Fig. 2 is a bottom plan view of the structure 40 illustrated in Fig. 1 showing certain parts thereof in slightly changed position;

Fig. 3 is a longitudinal sectional elevational view of my improved desk structure and support therefor as viewed substantially on the line 3—3 of Fig. 2, except that the desk unit is shown in 45 inoperative position within its container;

Fig. 4 is a transverse sectional elevational view taken substantially as indicated by the line 4—4 of Fig. 3;

Fig. 5 is a fragmentary sectional elevational view of adjacent portions of the desk member and its container when the desk member is in 50 operative position;

Fig. 6 is a fragmentary bottom plan view of a desk supporting member or container illustrat-

ing a slightly modified construction of certain of the desk supporting elements;

Fig. 7 is a longitudinal sectional view of the structure illustrated in Fig. 6 and taken substantially as indicated by the line 7—7 thereof;

Fig. 8 is a fragmentary transverse sectional elevational view of a portion of the structure illustrated in Fig. 7 and taken substantially as indicated by the line 8—8 thereof; and

Fig. 9 is a fragmentary sectional elevational view of a portion of the structure illustrated in Fig. 7 showing certain of the elements embodied therein in slightly changed position.

Referring particularly to Figs. 1 to 5, inclusive, the illustrative embodiment of the invention shown therein comprises a container, indicated as a whole by the numeral 11, and of relatively shallow box-like structure having an open end portion 12 adjacent which and, preferably, at opposite sides thereof, are provided suitable means, indicated as a whole by the numeral 13, for supporting the open or rear end portion of the container 11 on the dash or instrument panel 14 of a motor vehicle.

Each of the securing means 13 are shown, in 25 the present instance, as comprising a hook-like member 15 pivotally connected adjacent its lower end to the container 11 by means of a bolt 16 engaging a slot 17 formed in a bracket 18 secured to the side of the container 11, the bolt and slot 30 connection 16—17 permitting of relative bodily and pivotal adjustment of the member 15 with respect to the container.

The member 15, in the present instance, is provided with a hook-like supporting portion 19 35 adapted to engage the upper surface of a flange 21 formed on the dash or panel 14 and adapted to be secured to the flange 21 by means of a clamping screw 22 mounted on an ear 23 formed on the member 15 in a manner to engage the 40 underside of the flange 21 as clearly illustrated in Fig. 1, thereby providing efficient means for securing the open or rear end portion 12 of the container 11 to the dash or panel 14 of the automobile.

45 For rigidly supporting and retaining the opposite or forward end portion of the container 11 rigidly with respect to portions of the vehicle, a pair of spacing members 24 are provided adjacent the respective front corners of the container 11, each of the spacers 24 having a slot 25 formed therein adapted to receive a bolt 26 in a manner to permit relative movement of the spacer 24 and the container 11 to position the spacers 24 against the bulk-head or cowl, indicated at 27, of 50 55

an automobile, and in a manner to suitably position the forward end of the container 11 with respect thereto.

For urging the spacers 24 snugly against the cowl 27 in a manner to secure the forward end of the container in relatively fixed position with respect to adjacent portions of the vehicle, a supporting member, indicated as a whole by the numeral 28, is provided, and shown, in the present instance, as of substantially V-shape, pivotally mounted at 29 on the underside of the container 11. The member 28, in the present instance, comprises a pair of telescoping leg portions 31 by which the length of the supporting member 28 may be varied, the lower end of the member 31 being provided with a screw-threaded sleeve portion 32 adapted to receive a threaded bolt 33 having a head portion adapted to be positioned in a recess or socket 34 formed, preferably, in a base member or wear-piece 35 shown, in the present instance, as mounted on the floor board 36 of the vehicle.

It will be observed from the foregoing description that, by such an arrangement, after suitably positioning the spacers 24 in a manner to arrange the forward end of the container 11 at the angle desired with respect to the bulk-head or cowl 27 of the vehicle, the telescoping leg portions 31 of the supporting member 28 may be extended, if found necessary, and as desired, and the screw-threaded bolt 33 actuated to engage the socket 34 and forced there-against in a manner to cause the spacers 24 to snugly engage the bulk-head or cowl 27 of the vehicle and retain the front end portion of the container 11 rigidly in relatively fixed position with respect to the vehicle body.

Slidably mounted in the container 11 is a desk unit, indicated as a whole by the numeral 37, having an open side portion 38 adapted to receive a plurality of drawers or receptacles 39 for containing papers, writing material, or other supplies and having handle recesses 40 for conveniently withdrawing the drawers from the desk unit if and when desired. The desk unit 37 is adapted to be positioned in the container 11 when in inoperative position and to be withdrawn therefrom to operative position outside the container as illustrated in Fig. 1, the desk unit being provided with a plate or cover member 41 adjacent its rear end portion for reinforcing the desk unit and concealing portions of the operating mechanism.

For supporting the desk unit 37 in operative position, the container 11 is provided with a strut 42 of substantially V-shaped form having the forward end of its leg portions pivotally related to the forward end portion of the container 11, as indicated at 43, the rearward end of the strut 42 being pivotally connected, as indicated, at 44, to a link 45 pivotally mounted intermediate its ends, as indicated at 46, to a member 47 positioned in an elongated aperture 48 formed in the bottom portion of the receptacle 11 and slidably mounted therein, the strut 42 and link 45 being adapted to be folded into substantially parallel relation with respect to the container 11, as illustrated in Figs. 3 and 4, when the desk unit 37 is positioned in the container 11, or in inoperative position.

For actuating or moving the strut 42 and link 45, out of parallel relation with the container 11 and into operative position when the desk unit 37 is withdrawn from the container 11, the upper end portion 49 of the link 45 is adapted to extend

into the container 11 as shown in Figs. 3 and 5 in a manner to be engaged by an actuating bail 51 mounted on the desk unit 37 at the forward end thereof and extending downwardly between the sliding supports or runners 52 of the desk unit 37 and below the plane of the bottom portion of the desk unit in a manner to engage the upper end portion 49 of the link 45 as shown in Fig. 5, thereby moving the member 47 longitudinally of the aperture 48 and swinging the outer, lower or free end of the link 45 about its pivotal connection 46 in a manner to position the strut 42 and link 45 in the position shown in Fig. 1, the end portion 49 of the link serving also to limit the movement of the desk unit 37 with respect to the container 11 and prevent its complete withdrawal therefrom.

Mounted on the desk unit 37 and pivotally connected thereto adjacent its rear end portion in one or another of several apertures 53 formed in brackets 54 is a brace member 55 of substantially V-shape having a plate 56 secured to its forward end, the plate 56 being provided with a recess 57 adapted to engage the link 45 and having an enlarged portion 58 (Fig. 2) adapted to cooperate with a relatively wide portion 59 adjacent the lower end of the link 45 in a manner to secure the brace member 55 against accidental displacement with respect to the link.

For conveniently actuating the brace member 55 from the rear end portion of the desk unit 37 in a manner to position the brace member in operative position with respect to the link 45, a manually operated oscillating rod 61 is mounted in brackets 62 secured to the lower side of the desk unit 37 and provided adjacent one of its ends, and rearwardly of the desk unit, with a laterally extending handle portion 63, and at its opposite end with an elongated connector, loop or crank portion 64 adapted to receive one of the leg portions of the brace member 55 in a manner to raise and lower the forward end of the brace member when the rod 61 is oscillated, thereby enabling the operator to conveniently position the recess 57 of the plate 56 in operative position with respect to the link 45.

The operation of the device as above described is substantially as follows:

Assuming that the desk unit 37 is positioned within the container 11, by drawing outwardly on the handle portion 63, the desk unit may be withdrawn from the container to the position illustrated in Fig. 1, the withdrawal of the desk unit 37 causing the actuating bail 51 mounted thereon to engage the upper end portion 49 of the link 45 in a manner to move the member 47 longitudinally of the aperture 48 and to swing the arm 45 about its pivot 46 to position the pivotal connection 44 of the arm 45 and strut 42 as shown in Fig. 1. Thereafter, by rotating the handle 63 in a manner to oscillate the rod 61, the brace member 55 through its connection with the loop 64 may be forced downwardly in a manner to position the lower end portion of the link 45 within the recess 57 formed in the plate 56 secured to the brace member, thereby providing a locking connection between the brace member 55, link 45, and strut 42 in a manner to securely support the outer, rearward or free end portion of the desk unit 37 as illustrated in Fig. 1.

Thereafter, when it is desired to again position the desk unit within the container, it is necessary only to disconnect the lower end portion of the link 45 from the recess 57 formed in the

plate 56 and by rotating the handle 63 in the opposite direction to position the brace member 55 against the bottom of the desk member, after which the desk member may be moved into the 5 container, and in so doing, the member 47 will be moved longitudinally of the elongated aperture 48 in the opposite direction and the link 45 into substantially parallel relation with respect to the bottom of the container as illustrated 10 in Fig. 3.

From the foregoing description, it will be apparent that the present invention provides a novel construction and arrangement for conveniently supporting the container 11 with reference to the vehicle body and for readily withdrawing the desk unit 37 to operative position and conveniently and efficiently supporting the desk unit with respect to the container 11.

Referring to Figs. 6 to 9, inclusive, wherein a 20 slightly modified arrangement of supporting elements is shown, a bail-like strut 42a is pivotally connected adjacent its respective forward end portions, indicated at 43a, to crank arms (one crank arm being shown) 65 formed at opposite 25 ends of a rock shaft 66 rotatably mounted in brackets 67 secured to the underside of the container 11a, the central portion of the rock shaft 66 being provided with a laterally extending finger 68. The rear end portion of the strut 42a 30 is pivotally connected to a link 45a in substantially the same manner and for a like purpose as pointed out with reference to the structure illustrated in Figs. 1, 2, 3, and 5.

In the structure illustrated in Figs. 6 to 9, 35 however, the link 45a is pivotally mounted on an elongated substantially U-shaped member 69 having its rear end portion slidably mounted in an elongated aperture 48a formed in the bottom portion of the container 11a and its opposite or 40 forward end portion slidably mounted in a yoke or bracket 71 secured to the bottom of the container, the sides of the member 69 being provided with elongated slots 72 to permit the passage of 45 the rock shaft 66 therethrough in a manner to position the finger 68 within and between the sides of the sliding member 69.

Formed in the bottom portion of the U-shaped member 69 is an elongated aperture 73 adapted to be engaged by the finger 68 when the aperture 50 is brought into register therewith by the movement of the member 69 longitudinally of the container, as illustrated in Fig. 9, in a manner to rock the shaft 66 to position the pivotal connection 43a of the strut 42a and arm 65 on opposite 55 sides of the rock shaft 66, as indicated by dotted lines in Figs. 6 and 7, thereby positioning the pivotal connection 44a of the link 45a and strut 42a further to the rear of the open end portion 12a of the container 11a than is possible in the 60 structure illustrated in Figs. 1 to 5 of the drawings, and providing a structure whereby the brace member 55 of the desk unit 37 may be more readily adjusted to a horizontal writing position when the relative angle of the container 11a is 65 changed by varying conditions of installation of the container 11a with relation to the dash and cowl of an automobile, indicated at 14 and 27 (Fig. 1), and may be conveniently actuated without interference with the open end portion of 70 the container, and without raising the extreme rear end portion of the desk unit in positioning the brace member in substantially parallel relation to the desk unit for insertion therewith into the container when the desk unit is moved to 75 inoperative position.

For urging the finger 68 into the aperture 13 to insure rocking of the shaft 66 in the proper direction when the U-shaped member 69 is moved in either a rearwardly or forwardly direction, a pair of flat springs 74 and 75 are mounted 5 on the underside of the container 11a in a manner to engage the finger 68 when in either its rearward or forward position within the U-shaped member 69 as clearly illustrated in Figs. 6, 7, and 9.

The operation of the structure illustrated in Figs. 6 to 9, inclusive, is substantially like that described with reference to the structure illustrated in Figs. 1 to 5, except that in the structure shown in Figs. 6 to 9, inclusive, the link 45a is 15 pivotally connected to an elongated substantially U-shaped member 69 slidably mounted in the elongated aperture 48a adjacent one of its ends and in a yoke or bracket 71 at its opposite end, while the strut 42a instead of being pivotally connected directly to the container 11a is connected to crank arms 65 formed at opposite ends of the rock shaft 66, and the rock shaft is provided with a finger 68 positioned within the U-shaped member 69 having an aperture 73 formed therein. In moving the desk unit 37a outwardly from within the container 11a, shown in Figs. 6 to 9, the bail 51a when brought into engagement with the end portion 49a of the link 45a will cause the elongated U-shaped member 69 to be 30 moved longitudinally until the aperture 73 formed therein is brought into position beneath the finger 68, whereupon the flat spring 74 will force the finger downwardly into the recess 73 to be engaged by the material at one end thereof, and continued movement of the U-shaped member 69 will move the finger to the opposite side of the pivotal center of the rock shaft 66, thereby 35 rocking the shaft and positioning the pivotal connection 43a of the cranks 65 with the strut 42a as shown in dotted lines in Fig. 7, thus changing the position of the pivotal connection 43a and permitting the connection 44a between the link 45a and strut 42a to be positioned further rearwardly of the open end portion of the 40 container 11a than is possible in the structure 45 illustrated in Figs. 1 to 5, wherein the strut is pivotally connected directly to the container.

Upon movement of the U-shaped member 69 in the opposite direction, when the desk unit 37a 50 is moved to within the container, the finger 68 of the rock shaft 66 will be forced downwardly through the aperture 73 by the flat spring 75 in a manner to be engaged by the material at the opposite end portion of the recess and moved or 55 returned to the full line position shown in Fig. 7.

It will be observed from the foregoing description that the present invention provides a novel construction and arrangement whereby the pivotal connection of the strut 42a and link 45a 60 may be positioned a substantial distance rearwardly of the open end portion of the container and the pivotal mounting of the link for the purpose specified, and that the invention also provides a novel desk construction and arrangement 65 whereby the desk unit may be conveniently stored in an out-of-the-way position in an automobile or other vehicle, and wherein the desk unit may be conveniently and readily withdrawn and supported for use as a work table or the like. 70

Obviously, the present invention is not limited to the precise construction and arrangement shown and described as the same may be variously modified. Moreover, all the features of the invention need not be used conjointly as the 75

same may be used to advantage in variously different combinations and subcombinations.

What I claim as new and desire to secure by Letters Patent is:

from the open end thereof to operative position, a strut pivotally related to said container adjacent the forward end thereof, a member slidably mounted on said container, a link pivotally mounted intermediate its ends on said member, said link and strut being pivotally connected at their adjacent ends and foldable into substantially parallel relation with respect to said container when said unit is in operative position, means on said desk unit engageable with a portion of said link for moving said member and the pivotal connection of the link relatively to said container and for moving the link and strut out of parallel relation to the container when the desk unit is in operative position, and a brace member pivotally mounted on said unit adjacent the rear end thereof and detachably connected to the lower end of said link for supporting the desk unit in said operative position, and foldable into substantially parallel relation with respect to said desk unit for insertion therewith into said container when the desk unit is moved to inoperative position.

9. A desk for automobiles comprising a container having an open end, clamping means adjacent said end for securing the container to an automobile dash, adjustable means adjacent the opposite end of said container and engageable with portions of the automobile under the cowl for securing the container rigidly thereto, a desk unit slidably mounted in said container to be positioned therein when in inoperative position, and adapted to be drawn from the open end thereof to operative position, a strut pivotally related to said container adjacent the forward end thereof, a member slidably mounted on said container, a link pivotally mounted intermediate its ends on said member, said link and strut being pivotally connected at their adjacent ends and foldable into substantially parallel relation with respect to said container when said unit is in inoperative position, means on said desk unit engageable with the opposite end of said link for moving said member and the pivotal connection of the link relatively to said container and for moving the link and strut out of parallel relation to the container when the desk unit is in operative position, a brace member pivotally and adjustably mounted on said unit adjacent the rear end thereof and detachably connected to the lower end of said link for supporting the desk unit in said operative position, and foldable into substantially parallel relation with respect to said desk unit for insertion therewith into said container when the desk unit is moved to inoperative position, and manually operated means for moving said brace member into operative position with respect to said link.

10. A desk for automobiles comprising a container having an open end, securing means on said container engageable with portions of an automobile under the cowl thereof for securing the container rigidly thereto, a desk unit slidably mounted in said container and adapted to be drawn from the open end thereof, a strut pivotally related to said container adjacent the forward end thereof, a link pivotally related intermediate its ends to the container adjacent said open end and connected at one of its end portions to said strut, means on said desk unit engageable with the opposite end portion of said link for moving the link about its pivot into operative position and for limiting the movement of the desk unit with respect to said container, and a brace member pivotally mounted on said desk unit and en-

gageable with the first mentioned end portion of said link for supporting the desk unit in operative position.

11. A desk for automobiles comprising a container having an open end, securing means on said container engageable with portions of an automobile under the cowl thereof for securing the container rigidly thereto, a desk unit slidably mounted in said container to be positioned therein when in inoperative position, and adapted to be drawn from the open end thereof to operative position, a rock shaft rotatably mounted on the container and having crank arms adjacent its opposite ends and a laterally extending finger intermediate its ends, a bail-like strut having its opposite end portions pivotally connected to the free ends of said crank arms, an elongated member slidably mounted on said container, said slideable member having an aperture formed therein adjacent one of its ends adapted to receive said laterally extending finger when brought into register therewith for rocking said shaft when the said member is moved in either directions with respect to the container, resilient means on said container at opposite sides of said rock shaft for urging said finger into said aperture, a link pivotally mounted intermediate its ends on said slideable member adjacent the opposite end thereof, said link being pivotally connected at one of its end portions to said strut adjacent the central portion thereof and foldable with the strut into substantially parallel relation with respect to said container when said unit is in inoperative position, means on said desk unit engageable with the opposite end portion of said link for moving said slideable member and rotating said rock shaft and cranks, and for moving the link and strut out of parallel relation with respect to the container when the desk unit is moved to operative position, and a brace member pivotally mounted on said unit adjacent the rear end thereof and detachably connectable to the lower end of said link for supporting the desk unit in said operative position, said brace member being foldable into substantially parallel relation with respect to said desk unit for insertion therewith into said container when the desk unit is moved to inoperative position.

12. A desk for automobiles comprising a container, clamping means mounted on an adjustable pivot adjacent one end of said container for securing the container to an automobile dash, adjustable means adjacent the opposite end of said container engageable, respectively, with the cowl and floor of the automobile for securing the container rigidly thereto, and a desk unit mounted in said container and adapted to be drawn from one end thereof.

13. A desk for automobiles comprising a container, a pair of clamping members mounted on adjustable pivots adjacent one end of said container for securing the container to an automobile dash, means adjacent the opposite end of said container for securing the container rigidly to the automobile said means comprising a pair of spacers adjustably mounted adjacent said opposite end of the container and engageable with the cowl of the automobile, a supporting member pivotally mounted adjacent said opposite end portion of the container and having adjustable means engageable with the floor of the automobile for urging said spacers snugly against said cowl, and a desk unit mounted in said container and adapted to be drawn from one end thereof.
